UNITED STATES PATENT OFFICE.

JOSEPH H. BURKE, OF PORTLAND, MAINE.

CIRCULAR-SAW GUARD.

1,392,396.

Patented Oct. 4, 1921.

Application filed November 10, 1919. Serial No. 337,074.

To all whom it may concern:

Be it known that I, JOSEPH H. BURKE, a citizen of the United States, residing at Portland, in the county of Cumberland and 5 State of Maine, have invented certain new and useful Improvements in Circular-Saw Guards, of which the following is a specification.

My invention relates to guards for circular saws and the object of my invention is to devise a guard that may be quickly and easily adjusted, that is applied to and removed from the saw and which shall form an efficient protection against accidents.

15 To constitute a really effective guard, the device must be quickly and easily applied and removed, so that the men will take the time to use it and when removed, it must be swung out of the way, so as not to interfere with the work.

20 My invention is designed to fulfil these conditions. It consists essentially of a post depending from a point of support overhead and at one side of the saw with a hood 25 for protecting the saw secured to the lower end of a rod, which extends from the saw to the post and which is clamped to the post and arranged to be adjusted vertically and to be rotated with respect to the post. The 30 rod is clamped by a single set screw and when it is in position a portion of the rod drops into a socket by which it is accurately located with respect to the saw.

The invention may be best understood by 35 reference to the accompanying drawing wherein is shown a device constructed in accordance with my invention. It is to be understood, however, that other forms of the invention may be constructed which will 40 come within the terms of the invention as set out in the claims.

In the drawing,

45 Figure 1 is a front elevation showing a portion of the table and saw guide in section, on the line 4—4 of Fig. 2.

Fig. 2 is a side elevation partly in section,

50 Fig. 3 is a section taken on the line 1—1 of Fig. 1,

Fig. 4 is a section taken on the line 2—2 of Fig. 1 and,

Fig. 5 is a section taken on the line 3—3 of Fig. 2.

Referring to the drawing, 15 represents 55 the saw, 16 the table and 17 the saw guide.

The guard is held in place by a post 4 depending from some suitable overhead support and braced by guys 5.

The hood for protecting the saw is held by a rod which is so connected to the post 60 that it may be adjusted vertically and rotated at the same time.

As shown, the post is made in the form of a hollow tube or pipe, the lower end of which is formed into a square socket for a 65 short distance from the end.

The rod for supporting the hood is in two parts, the upper one 6, being L-shaped and extending out from the post to a point 70 directly over the saw. The rod is preferably made of a square metal bar which fits the socket in the post when the hood is in place on the saw.

Below the upper end of the bar at 7 it is 75 reduced in size for some distance, so when the bar is lifted, the reduced portion will come in the socket and will enable the bar to be turned. The tube above the socket is large enough to allow the square portion 7, 80 of the bar to turn and the reduced portion 7 is long enough to allow this to be done.

The hood 8 is attached to the lower end of the vertical rod 9, the upper end of the rod being secured by a set screw 10, to the 85 outer end of the rod 6. The rod 9 and the rod 6 are rabbeted or otherwise interlocked, so that when secured together they will always take the same relative position. As here shown, the rod 9 contains a rabbet on one side into which the square bar 6 fits, so 90 that it will take a vertical position either downward or upward.

The hood 8 is in the form of a section of a saw and is preferably made shallow vertically, so that it can be used with many diameters. It is only necessary to cover directly that portion of the saw which projects up through the wood being sawed which is very little. The rod 9 is attached 95 to the hood back of the center, so that the hands of the operator will not be interfered with.

To prevent the teeth of the saw coming in contact with the side of the hood, I secure on the inner side of the hood knobs or projections 11 which are adapted to strike against the smooth face of the saw, if the hook is swung to one side sufficiently to hit the saw.

It sometimes happens that a board hav-

ing passed the saw is thrown backward and if the operator is reaching over from the front to the rear of the saw to clear the board, as frequently happens, the hand may 5 be drawn onto the saw.

To prevent this, I make use of a toothed pawl 12, which is pivoted to the rear end of the hood inclining rearwardly, so that any tendency of the wood to be thrown forward 10 by the saw is checked. To facilitate inspection of the work, while the saw is working, I insert in the front end of the hook, a small window 14 of some transparent material as mica.

15 In using the invention, the hood is secured normally in place covering the saw. When it is desirable to remove the hood for any purpose, the set screw 13 is released, allowing the rod 6 to be pushed up into the 20 post 4 and turned around to be out of the way.

If still more room is desired on the table, the rod 9 may be swung up into the position shown in dotted lines in Fig. 1.

25 The first operation is done very quickly, one hand manipulating the set screw and the other hand lifting and turning the hood. The entire space above the saw is then free and can be used for sawing the ends of 30 pieces that have to be held upright.

The operation of placing and displacing the hood is so readily and quickly done that men will use it where they would not, if it was more complicated or required more time.

35 It is to be noted that by having the rod 6 exactly fit the socket in the post 4, the hood will automatically drop into its exact position when it is lowered onto the saw. It will thus require no exact adjustment 40 laterally and will never come in contact with the saw by reason of being out of position sidewise. It is only the vertical position that the operator has to look out for and this is adjusted according to the thickness 45 of the stock which is being sawed.

Indicating marks may be made on the rod 6, where it enters the post 4 to indicate the height of the hood when stock of different thicknesses is to be sawed.

50 I claim:

1. In a guard for circular saws, the combination of a tubular dependent post at one side of the saw, said post having an angular socket at its lower end, an L-shaped rod having its upper end fitting said socket and a portion below said end reduced in size and adapted to rotate in said socket, a hand clamp for clamping said rod in place in said post, a vertical rod on the end of said L-

shaped rod and a hood on the lower end of 60 said vertical rod adapted to cover the saw.

2. In a guard for circular saws, the combination of a tubular dependent post at one side of the saw, said post having an angular socket at its lower end, an L-shaped rod having its upper end fitting said socket and a portion below said end reduced in size and adapted to rotate in said socket, a hand clamp for clamping said rod in place in 65 said post, a vertical rod removably clamped on the end of said L-shaped rod and a hood on the lower end of said vertical rod adapted to cover the saw.

3. In a guard for circular saws, the combination of a dependent post at one side of 75 the plane of the saw, a vertical rod slidably and rotatably mounted in said post, a hand clamp for clamping said rod to the post, a protecting hood for said saw and a connecting member by which said hood is solely 80 supported, said member rigidly connecting said hood with the lower end of said rod, whereby said hood may be lifted and swung laterally clear from said saw by a single motion.

4. In a guard for circular saws, the combination of a dependent post at one side of 90 the saw, a vertical rod slidably and rotatably mounted on said post, a hand clamp for clamping said rod in position on said post, an offset member extending from the lower end of said rod to a point over the saw, a hand screw in the end of said offset, a vertical rod clamped to the end of said offset by said hand screw and rotatable thereon 95 when not clamped and a hood for the saw on the lower end of said vertical rod and supported solely thereby.

5. In a guard for circular saws, the combination of a tubular dependent post at one 100 side of the saw having a square socket at its lower end, an L-shaped square bar extending into said post and having a portion below its upper end cut away so as to be rotatable in said socket, a hand clamp screw for clamping said bar in said post, a hand clamping screw in the lateral end of said L-shaped bar, a square vertical rod through the upper end of which said screw passes and which is rotatable on said screw when the latter is 110 loosened, a shoulder being formed on said vertical rod to prevent turning when clamped in place and a hood on the lower end of said vertical rod.

In testimony whereof I have affixed my 115 signature.

JOSEPH H. BURKE.
